(57) CLAIM

The ornamental design for a cutting tool with W-shaped flute gully, as shown and described.

DESCRIPTION

FIG. 1 is an isometric top view of a cutting tool showing our new design with nineteen W-shaped flutes;

FIG. 2 is a side view of the cutting tool of FIG. 1;

FIG. 3 is a front view of the cutting tool of FIG. 1;

FIG. 4 is a rear view of the cutting tool of FIG. 1; and,

FIG. 5 is a cross sectional view of the cutting tool showing our new design with nineteen W-shaped flutes, taken along line 5-5 in FIG. 2.

1 Claim, 4 Drawing Sheets
